UNITED STATES PATENT OFFICE

2,520,240

CATHODE-RAY TUBE

Leslie E. Flory, Princeton, N. J., assignor to Radio Corporation of America, a corporation of Delaware

Application September 5, 1946, Serial No. 695,015

3 Claims. (Cl. 315—11)

1

This invention relates to a cathode ray pickup tube of the type disclosed in the patent issued jointly to George A. Morton and myself, No. 2,345,282, on March 28, 1944. In this type of tube, known as the Orthicon, a beam of electrons from an electron gun is magnetically deflected to scan a mosaic which is essentially at cathode potential so that in darkness the beam electrons do not strike the mosaic but are returned to the gun end of the tube. If the entire tube is in an axial magnetic field the beam will return approximately along the same path over which it approached the mosaic. When areas of the mosaic are caused to become positive, as for instance by electron emission in response to a light image, the positive areas collect electrons from the beam and return the mosaic to the original condition of equilibrium. These electrons are subtracted from the returning beam resulting in a modulation of the returning beam current. This returning beam may be collected at the gun end in an electron multiplier or other collector and thus constitute the television signal.

In tubes of this type of usual construction the returning beam is shifted so that it can enter an electron multiplier placed alongside the gun.

Since it is necessary to accelerate the electron beam to several hundred volts in order to maintain the beam in good focus, it is also necessary to decelerate it in the region of the mosaic. Therefore, in previous tubes an electric field exists in the region of the mosaic, the lines of force of which are curved. As the electron beam enters the decelerating electric field it encounters the condition where the electric field and the magnetic field are at a relatively great angle with respect to each other. Under these conditions the beam is deflected from its original course by an amount dependent upon the component of the electric field at right angles to the magnetic field and in a direction mutually perpendicular to both. When the beam is reversed in direction near the mosaic and re-accelerated, it is again deflected in the same direction, adding to the deflection taking place during deceleration. The electron beam, therefore, does not return over the same path by which it approached the mosaic. Furthermore, the angle between the magnetic field and the electric field becomes greater as the distance from the tube axis is increased. Thus as the beam is deflected to scan the mosaic, the deviation of the return beam from the original path varies in accordance with the deflection, resulting in the return beam scanning the multiplier dynode and making it diffi-

cult to properly utilize the beam with a multiplier.

It is an object of this invention to reduce the scanning pattern of the return beam so it may readily enter the opening of an electron multiplier for all deflected positions of the beam at the mosaic.

Another object of the invention is to provide means for producing an electric decelerating field in front of the mosaic with lines of force parallel to the lines of the electromagnetic field.

Another object of the invention is to produce a decelerating field having parallelism of the lines of the electric and magnetic fields by means of a mesh of very fine wires.

Other objects will appear in the following specification, reference being had to the drawing in which:

Fig. 1 illustrates the curved lines of the electric field which produces the undesired scanning pattern on the multiplier dynode;

Fig. 2 is a section showing the application of my invention to television pickup tubes of the Orthicon type;

Fig. 3 illustrates the effect of the screen or mesh of my invention in making the electric lines of force of the decelerating field substantially parallel to the electromagnetic lines in the region of greatest decelerating field.

Referring to Figure 2 of the invention, the tube comprises an evacuated envelope 1 of glass or other suitable material containing the gun G at one end and the target T at the other. The gun G consists of the usual indirectly heated cathode 2, grid 3 and first anode 4. The grid and anode have the usual small apertures for forming the outgoing or primary cathode ray beam B. Inside the envelope 1 is placed an accelerating second anode 5 which may be plated on the inside wall or mounted separately thereof. This anode is usually called the wall coating regardless of its manner of mounting.

Outside the tube envelope 1 is located the electromagnetic deflection unit 6 which has two coils producing fields at right angles to each other and to the axis of the tube. These coils are not separately shown. One coil is supplied with a suitable varying voltage for line scansion and the other with one for frame scansion. These sources of deflection voltage are well known in the art.

Outside the deflection unit 6 is located the electromagnetic focusing coil 7 energized by direct current to produce a suitably strong magnetic focusing field axially of the tube and per-

2

pendicular to the target. Between the wall coating 5 on the inside of the envelope 1 and the target T is placed the decelerating anode or lens 8. To reduce the scanning of the multiplier dynode 9 by the return beam, I employ a mesh of very fine wires 10 in front of the mosaic 11 and between it and the decelerating lens. It is operated at a positive voltage with respect to the mosaic on the target T, preferably at about the voltage of the anode 8 which may be 50 volts when the wall coating anode is from 100 to 200 volts. The target as usually constructed comprises a thin transparent sheet of mica 12 in which is plated a thin transparent film 13 of metal such as platinum, for example (Figs. 2 and 3). The mosaic 11 is formed on the side of the mica opposite the side containing the metal film and facing the gun. It may consist of a layer of discrete particles of material capable of emitting photo electrons when energized by light imaged thereon as is well understood in the art.

To direct the return beam B_1 away from the anode 4 and into the first dynode of the multiplier 9, one stage only being shown for simplification, a pair of lifter plates 14, 15 are employed. These are placed between the gun and the target suitably near the former. These are shown in said patent and this action on the beams B and B_1 is well known.

The metal film of the target may be connected to the power supply unit conventionally shown at V so as to have substantially the potential of the cathode 2 of the gun. This source may also supply proper potentials to the other electrodes of the tube.

When the screen 10 is not employed the electric field lines E are out of parallelism with the electromagnetic lines M which are parallel to the axis of the tube after passing beyond the deflection coils. When the fine mesh screen 10 is used in front of the mosaic the electric field lines E are substantially parallel to the electromagnetic lines M throughout the greater part of the deceleration field.

The deceleration and re-acceleration of the beam electron takes place in a region where the field lines are approximately parallel to the tube axis and, therefore, the undesired deflection is much reduced.

While certain specific embodiments have been illustrated and described, it will be understood that various changes and modifications may be made therein without departing from the spirit and scope of the invention.

What I claim as new is:

1. A television pick-up tube system, comprising an evacuated envelope containing a cathode-ray beam gun having cathode, grid and anode electrodes; a target spaced from the gun, a fine mesh screen facing said gun adjacent said target and a second anode electrode for producing a field for accelerating electrons, means for producing a magnetic focusing field between the gun and the target and a voltage source connected to produce potentials at said electrodes, said

target and said screen, the potentials produced at said target and said cathode being substantially the same and the voltage between said screen and said target producing throughout the space therebetween a decelerating field having electrostatic lines parallel to the magnetic lines of said focusing field.

2. A television pick-up tube system, comprising an evacuated envelope containing a cathode ray beam gun having cathode, grid and anode electrodes, a target spaced from the gun comprising a transparent sheet with a photocathode on the side thereof facing said gun and a transparent electrode on the other side thereof, a fine mesh screen facing said gun adjacent said photocathode and a second anode electrode for producing a field for accelerating electrons between said target and said gun, means for producing a magnetic focusing field between the gun and the target and a voltage source connected to produce potentials at said electrodes and said screen, the potentials of said transparent electrode and said cathode being substantially the same and the voltage between said screen and said transparent electrode producing throughout the space between the screen and the target a decelerating field having electrostatic lines parallel to the magnetic lines of said focusing field.

3. A television pick-up tube system, comprising a tube containing a cathode ray beam gun, having cathode, grid and anode electrodes, a target, a second anode electrode between the gun and target, a multiplier dynode at one side of the gun, a fine mesh screen facing said gun adjacent said target, and a decelerating anode between the second anode and the screen, means for producing a magnetic focusing field between the gun and the target, field producing means for scanning the beam of said gun over said target, and a voltage source connected to produce potentials at said electrodes, said target and said screen, the potentials applied to said cathode and said target being substantially the same, the potential of said screen being intermediate those of said decelerating anode and said target to provide a decelerating and accelerating field between the screen and target parallel with the focusing field at all elemental areas of the target raster whereby the return beam leaves the target and is accelerated towards said gun along substantially the same paths as the outgoing beam and lifter anodes for changing the path of the electrons and directing them to said multiplier dynode.
